(57) **CLAIM**

The ornamental design for a tire tread, as shown and described.

DESCRIPTION

FIG. 1 is a front view of the tire tread design, the rear view being identical thereto;

FIG. 2 is a right side view thereof;

FIG. 3 is a left side view thereof;

FIG. 4 is an enlarged partial front view thereof; and,
FIG. 5 is a front, right perspective view thereof.

The broken line showing is for the purpose of illustrating unclaimed portions of the tire tread and forms no part of the claimed design. The tread pattern repeats uniformly throughout the circumference of the tire.
